CAP FOR ENDS OF CUE STICKS

Filed May 28, 1923

FIG. 1.

FIG. 2.

FIG. 3.

FIG. 5.

FIG. 4.

Inventor

Zoran Krstich

UNITED STATES PATENT OFFICE.

ZIVAN KRSTICH, OF SOUTH OMAHA, NEBRASKA.

CAP FOR ENDS OF CUE STICKS.

Application filed May 28, 1923. Serial No. 241,998.

To all whom it may concern:

Be it known that I, ZIVAN KRSTICH, a citizen of the United States, residing at South Omaha in the county of Douglas and State 5 of Nebraska, have invented certain new and useful Improvements in Caps for Ends of Cue Sticks, of which the following is a specification.

This invention relates to a pool or billiard 10 cue and more particularly to one in which the tip is detachably secured thereto.

Another object of the invention is to provide the cue with a screw threaded sleeve 15 having slots or grooves therein to receive longitudinally extending gripping members 20 therein for engaging the tip and holding the same in position.

A further object of the invention is to provide an interiorly threaded ferrule which 25 passes over the tip of the cue and abuts the upper end of the cue, and this end is designed to screw threadedly engage the sleeve for holding the tip securely in place.

A still further object of the invention is 30 to provide the ferrule with a circular opening in one side thereof to receive a thumb screw therein to prevent accidental displacement of the ferrule from the cue.

Referring to the drawings in detail where- 35 in like characters of reference denote cor- responding parts,

Figure 1 is a side view of the end of a pool or billiard cue with my invention ap- plied thereto,

Figure 2 is a sectional view taken on line 2-2 of Figure 1,

Figure 3 is a longitudinal sectional view of the invention,

Figure 4 is a sectional view taken on line 40 4-4 of Figure 2, and

Figure 5 is a detail view showing the cue tip.

Referring to the drawings in detail, the numeral 1 indicates a pool or billiard cue 45 and the upper end 2 is designed to receive a metallic sleeve 3 which is screw-threaded, said sleeve having grooves or slots 4 formed therein to receive longitudinal gripping members 5 which may be soldered or other- 50 wise secured to the metallic member.

A ferrule 6 has its lower end interiorly threaded and is designed to pass over the tip 7 of the cue and screw threadedly en- gage the metallic member 3, which is se- 55 cured to the upper end of the cue. The gripping members have fingers 8 formed on

the outer or upper end thereof as at 9 for engaging the sides of the tip for holding the same in an associated position. An opening 10 is formed in one side of the ferrule intermediate its ends and is de- signed to receive a thumb screw 11 which passes through a circular opening formed in the metallic member for preventing the accidental displacement of the ferrule from 65 the upper end of the cue.

Among some of the advantages to be de- rived by the use of this device, it may be stated that the frequent displacement of the tips of billiard cues occasioned by the 70 fracture or breakage of the glue or similar adhesive, and the resulting delay required for repairs, may be avoided, and it is also understood that the tips may be readily re- moved when injured or worn, to be replaced 75 by new tips.

In view of the foregoing description of my invention, it is thought that any further explanation as to the construction, opera- 80 tion, and objects of same are unnecessary.

While I have shown and described the preferred form of my invention, I realize that various minor changes may be resorted to, without departing from the spirit and scope of the invention as claimed, and 85 therefore, I do not wish to limit myself to the exact details of construction shown, nor to the combination and arrangement of parts.

What I claim as new and desire to secure 90 by Letters Patent is:

1. In combination with a cue stick, of a metallic member secured thereto, said metal- 95 lic member having external screw threads thereon, spaced arms carried by said metal- lic member extending therefrom, gripping fingers upon the free ends of said arms, a tip received between said arms, said tip having recesses therein for receiving said fingers, and a ferrule adapted to be slipped over said tip and arms and threaded on said metallic member, said ferrule receiving the inner end of said tip to hold the same rigid- 100 and to also hold the fingers in the recess in said tip.

2. In combination with a cue stick, of a metallic member secured thereto, said metal- 105 lic member having external screw threads thereon, spaced arms carried by said metal- lic member and extending therefrom, grip- ping fingers upon the free ends of said arms, a tip received between said arms, said

tip having opposite grooves therein for receiving portions of said arms, said tip also having recesses therein joining said grooves for receiving said fingers so that the outer surfaces of said arms and the periphery of said tip will be flush, and a ferrule adapted to be slipped over said tip and arms and threaded on said metallic member, said ferrule receiving the inner end of said tip

to hold the same rigid and to also hold the fingers in the recesses in said tip.

In testimony whereof, I have affixed my signature in the presence of two witnesses.

ZIVAN KRSTICH.

Witnesses:

ENOS R. LEIGH,
MARY C. KARASEK.
